Letters Patent, 2360, Dated July 17, 1864.
Design for Clock Case.

The schedule referred to in these Letters Patent and making part of the same

of all whom it may concern:

Be it known that I, F. J. Fracker of Boston
in the County of Suffolk and State of Massachusetts, have originated
and produced a new and ornamental design for a clock case
of which the following is a full and clear description referring
herein being had to the accompanying drawings making part of this
specification. The Design consists of a base A, upon which is main-
tained a standard B, having in its face the dial C, and being surmounted
by an urn or vase D, the outline of the whole being as shown in the drawing.
I claim the Design for a clock case as shown in the drawing.
